UNITED STATES PATENT OFFICE.

JOHN EDWARD DAVIS AND CHARLES ALBERT LEWIS, OF OLAX, NEBRASKA.

CAR-COUPING.

SPECIFICATION forming part of Letters Patent No. 430,247, dated June 17, 1890.

Application filed April 14, 1890. Serial No. 347,880. (No model.)

To all whom it may concern:

Be it known that we, JOHN EDWARD DAVIS and CHARLES ALBERT LEWIS, citizens of the United States, residing at Olax, in the county of 5 Custer and State of Nebraska, have invented certain new and useful Improvements in Car-Couplings; and we do declare the following to be a full, clear, and exact description of the invention, such as will enable others 10 skilled in the art to which it appertains to make and use the same, reference being had to the accompanying drawings, and to the letters of reference marked thereon, which form a part of this specification.

15 This invention relates to certain new and useful improvements in car-couplings, and it has more particular reference to that class of couplings in which provision is made for automatically coupling the cars, and in which 20 provision is also had for readily uncoupling the same without the necessity of passing between the cars.

The invention has for its object to simplify and cheapen the construction and at the same 25 time to render more serviceable in operation this class of coupling devices.

To the above ends, and to such others as the invention may pertain, the same consists in the peculiar construction and in the novel 30 combination, arrangement, and adaptation of parts, all as more fully hereinafter described, shown in the accompanying drawings, and then specifically defined in the appended claim.

35 The invention is clearly illustrated in the accompanying drawings, which, with the letters of reference marked thereon, form a part of this specification, like letters of reference indicating like parts throughout the several 40 views, and in which drawings—

Figure 1 is a perspective view of a portion of a car provided with our improved coupling device. Fig. 2 is a central longitudinal vertical section through the draw-head and 45 coupler.

Reference now being had to the details of the drawings by letter, A represents the draw-head, which is attached to the truck B of the car C in the usual way. The draw-head is made of cast metal, and the body of 50 the draw-head is in the form of a single cast-

ing, provided with the usual horizontal slot A' for the reception of the coupling-link, and the lower edge of the entrance to this slot is inclined downwardly, as shown at A², so as 55 to insure the ready coupling of cars in which the coupling attachments may differ in height, as will be readily understood. The upper face of the draw-head is provided with a central rectangular opening A³, having an 60 extension or neck A⁴, extending in the direction of the open end of the draw-head, as shown, while at the opposite or rear end of the opening the depression A⁵ in the upper face of the draw-head is provided for the re- 65 ception of the operating-latch, as will presently appear.

The coupling pin or hook D is made of cast metal and in substantially the form shown. The flat portion D' of the hook or pin is 70 adapted to enter the neck A⁴, and is pivotally retained therein by means of the transverse rod or pivot D², passed through a suitable opening formed for the purpose in the draw-head. The body portion D³ of the hook 75 D is adapted to fit within the opening A³, with its lower end, when in place, resting within a depression or seat D⁴, formed within the lower inner face of the slot within the draw-head. It will be observed that when 80 the hook D is in its normal or locked position the upper face of the hook will be flush with the upper face of the draw-head, and that there will thus be no uneven surfaces presented within which ice and snow might accumulate and possibly interfere with the free 85 operation of the device in the winter season.

E is a transverse rod, which is passed through a suitable opening formed for its reception in the draw-head. This rod passes 90 through the upper portion of the vertical opening A³, near its rear edge, and the ends of the rod are bent to form the operating cranks or handles E'. The latch F is secured at its rear edge to the bar E within the opening A³, and extends rearwardly, or in the direction of the rear end of the draw-head, resting normally within the recess or depression A⁵ at the rear end of the opening A³, and upon this latch normally rests the extension 95 G of the hook D.

H is a vertical rod adapted to be moved

vertically within suitable guides or keepers H', secured to the end of the car. This rod is designed to be of sufficient length to extend a short distance above the top of the car, 5 and is provided at its upper end with a suitable handle H', while at its lower end it is provided with a horizontal arm H², which is connected with the upper face of the hook D by a suitable link or chain H³, thus providing 10 a convenient means for raising the said hook D from the roof of the car when it may be desired to uncouple the cars from the roof.

Having thus described our invention, what we claim to be new, and desire to secure by 15 Letters Patent, is—

The herein-described improvement in car-couplings, the same comprising, in combination, the draw-head recessed at its forward end, as described, the rectangular vertical 20 opening in the upper face of the draw-head communicating with the recess, said vertical

opening being provided at one of its ends with an extension, as A⁴, and at its opposite end with a depression A⁵, the coupling-hook pivoted within the extension and adapted to 25 normally close the vertical opening with its upper face flush with the upper face of the draw-head, and the rod E, having operating-crank at its ends and provided at its longitudinal center with a latch, said latch being 30 fitted within the depression A⁵ beneath the end of the coupling-hook and adapted to raise the hook when actuated by the operating-lever, substantially as and for the purpose described. 35

In testimony whereof we affix our signatures in presence of two witnesses.

JOHN EDWARD DAVIS.

CHARLES ALBERT LEWIS.
